Application November 2, 1938, Serial No. 238,394

4 Claims. (Cl. 90—49)

(Granted under the act of March 3, 1883, as
amended April 30, 1928; 370 O. G. 757)

This invention relates to a universal shaper ram reverser attachment and has for an object to provide a means of quickly reversing a shaper ram in synchronism with the movement of the work carrying bed, particularly when the work involved is a propeller.

This attachment is intended for use on universal draw-cut shapers, particularly of the well known type shown in the Morton Patents Nos. 472,061; 550,004; 682,218; 983,748; 991,347; 1,167,648; 1,206,884, and 1,218,951, amongst others. When such universal draw-cut shaper is used for the particular work of operating on a propeller, it is necessary, when using the prior feed attachment, for the ram head that holds the cutting tool to make a full stroke on its return in order to actuate the mechanism that controls the feed of the saddle and of the work table in synchronism, regardless of how short a portion of the stroke is used in doing the actual cutting. This method is particularly undesirable because of the waste of time involved, as well as the unnecessary wear and tear on the heavy and expensive mechanism. In doing such propeller work, the cutting tool is in contact with the work only about one-third of the time during the first part of the cut. This cutting contact gradually changes as the cut goes over the blade until it crosses the center region of the blade. At this point the cutting tool is in cutting contact with the work during the full stroke but as the cut progresses further the same condition is approached as existed at the beginning of the cut. As the cutting continues the saddle carrying the cutter must be raised and the table carrying the propeller must be rotated in proper synchronism. With the attachment of this invention this necessary operation can be performed in synchronism while the motion of the ram itself can be limited so that the length of its stroke is substantially identical with the length of the cut instead of necessitating a full length stroke and a one-third more or less length cut as at present.

It may be stated that in ordinary shaper work the conventional clutch, connecting rod and quadrant therein operate the column and saddle feeds and the lengthening and shortening of the cut stroke does not interfere with the feed movements. However, on propeller work where a true pitch is to be machined, it is necessary to synchronize the movements of the saddle and the work, and because of this the standard feed mechanism of the machine is entirely disengaged. Prior to this invention an attachment was added

for synchronizing the movements of the saddle to the work but such prior attachment was dependent on the ram making a full length stroke, irrespective of the length of the cut. The present attachment of the present invention utilizes the conventional motion of the clutch, connecting rod and quadrant rather than the ram itself and synchronizes the movement of the saddle and the work irrespective of the length of this stroke of the ram.

It is also possible with this attachment to adjust the length of the stroke on the ram and thus of the cutter without stopping the operation of the machine, thus making a further saving of time available.

With the above and other objects in view the invention consists in the construction, combination and arrangement of parts as will be herein-after more fully described.

Reference is to be had to the accompanying drawing forming a part of this specification, in which like reference characters indicate corresponding parts through the several views, and in which:

25 Fig. 1 is a side elevational view of a draw-cut shaper partly broken away to which the feeding attachment of this invention has been applied;

Fig. 2 is a front elevational view of Fig. 1; and,

30 Fig. 3 is a top plan, partly fragmentary view of the control ratchet and tension friction brake thereon.

35 There is shown at 10 a universal shaper ram to which may be secured the cutter 11. This shaper ram 10 is reciprocally carried by the vertically movable saddle 12, the length of the stroke of the ram 10 being adjustably controlled by the tappets 13 and 14 in a conventional manner in the prior art and particularly described and shown at 46 and 47 in the patent to Morton, 550,004.

40 The saddle 12 may be vertically moved on the column 15 by the vertical elevator screw shaft 16. This shaft 16 is, in turn, geared to the horizontal shaft 17 by the beveled pinions 18 and 19. This horizontal shaft 17 extends through and is keyed to the control ratchet 20.

45 The other end of the horizontal shaft 17 is provided with a beveled pinion 21 geared to a beveled pinion 22 on a shaft 23 which, in turn, controls the rotation of a gear 24 forming with gear 25, a part of a gear train (not shown) for controlling the rotation of a work carrying table (not shown, but well known in the prior art and illustrated in some of the aforementioned patents).

It is apparent that rotation of control ratchet 20 will thus raise the saddle 12 and rotate the work table in proper synchronism, according to the size of the particular gears placed in the gear train, which, in turn, varies with the work being performed. The reciprocation of the ram 10 is caused by the oscillating friction clutch 26 in which operates the cross-head 27. Secured to the cross-head 27 is one end of the connecting rod 28, whose other end controls the oscillation of an arm 29 which is pivoted at 30. The free end of this arm 29 carries a geared quadrant at one end forming part of the usual feed mechanism, but in this case such quadrant is disconnected from its operating parts and hence is not shown.

The rod 28 and arm 29 are journaled together on one end of a shaft 30, being held thereon by the nut 53. The other end of this shaft 30 carried a friction clutch housing 31. This housing 31 includes a pair of clutch shoes 32 and 33 and friction linings 34 adapted to be tightened by means of adjusting screws 35 about a rod 36 extending therethrough. At the upper end, this rod 36 may be provided with a female socket 37 for attaching an additional piece of rod of the same diameter thereto. At the lower end, this rod 36 is pivoted to one end 38 of an arm 39 oscillatable about the shaft 11 as a center and closely adjacent to the control ratchet 20. Pivoted on the arm 39 at 40 is a pawl 41 provided with reversible pawl teeth 42 and 43, while a tension spring 44 anchored to the arm 39 at 45 urges the tooth 43 into mesh with the teeth of control ratchet 20. Obviously, rotating the pawl 41 about its pivot 40 will cause the other tooth 42 to mesh with the control ratchet 20 for reverse rotation of the control ratchet 20.

The oscillation of arm 39 is limited by the adjustable stops 46 and 47 supported on a bracket 48 on the base 49. An angle bracket 50 on base 49 carries a tension friction brake 51 adjustably pressing a pair of friction pads 52 against the sides of control ratchet 20 preventing momentum from causing the gear 29 to rotate beyond the amount it is positively urged by the oscillating pawl tooth 43 and likewise preventing accidental reversal of the control ratchet under the reverse drag of the pawl.

In operation, the tappets 13 and 14 are set to limit the travel of the ram 10 to the desired length, and may be adjusted while the machine is in operation to take care of a progressively changing length of cut. As the ram reciprocates, the oscillating clutch 26 causes connecting rod 28 to oscillate arm 29 about its pivot 30, all of this just mentioned mechanism being carried by the saddle 12, and thus moved vertically as the saddle rises or falls.

As the arm 29 is oscillated, it causes the shaft 30 to likewise oscillate. The shaft 30 is secured by the friction housing 31 to the rod 36 which is pivoted on the pawl carrying arm 39. Hence, as the arm 29 is oscillated, it causes the rod 36 to transmit this oscillation to the pawl carrying arm 39, which, in turn, through the pawl 41 causes the control ratchet 20 to rotate in one direction only a distance determined by the adjustable stops 46 and 47. As the control ratchet 20 is rotated, it rotates the horizontal shaft 11, which, as already described, causes the vertical screw threaded shaft 16 to move the saddle 12 vertically and simultaneously rotates the propeller or work carrying table in proper synchronism.

However, as the saddle is moved vertically, the

shaft 30 likewise moves vertically, and the friction housing 31 is so adjusted by means of the screws 35 that it will transmit the oscillation motion to the rod 36, but will slip to permit vertical movement between the housing 31 and the rod 36. In this manner, the saddle and its associated mechanism may move vertically yet transmit motion to the work carrying table in proper synchronism while the length of the stroke of the ram may be kept in minimum proportion to the length of the cut made by the ram. Each reciprocation of the ram causes one oscillation of the connection rod 28 and thus one oscillation of the pawl arm 39 and thus one measured and synchronized movement of the saddle and of the work table.

Other modifications and changes in the proportions and arrangements of the parts may be made by those skilled in the art without departing from the nature of the invention, within the scope of what is hereinafter claimed.

The invention described herein may be manufactured and/or used by or for the Government of the United States of America for governmental purposes without the payment of any royalties thereon or therefor.

Having thus set forth and disclosed the nature of this invention, what is claimed is:

1. In combination with a vertically movable and horizontally reciprocable shaper ram, a vertically movable ram carrying saddle, operating means for vertically moving the saddle, including a rotatable control ratchet, ram stroke controlling oscillatory means carried by said saddle for reciprocating said ram, and a ram attachment comprising means connecting said rotatable vertical control ratchet to said ram stroke controlling oscillatory means.

2. In combination with a vertically movable and horizontally reciprocable shaper ram, a vertically movable ram carrying saddle, operating means for vertically moving the saddle, including a rotatable control ratchet, ram stroke controlling oscillatory means carried by said saddle for reciprocating said ram, and a ram attachment comprising means connecting said rotatable vertical control ratchet to said ram stroke controlling oscillatory means, said connecting means including an oscillatory pawl carrying arm, a rod pivotally connected to said arm and a friction housing secured to said ram stroke controlling oscillatory means of said saddle, said friction housing embracing said rod to transmit the oscillatory motion of said saddle carried ram stroke controlling oscillatory means to said pawl carrying oscillatable arm.

3. In combination with a vertically movable and horizontally reciprocable shaper ram, a vertically movable ram carrying saddle, operating means for vertically moving the saddle including a rotatable control ratchet, ram stroke controlling oscillatory means carried by said saddle for reciprocating said ram, and a ram attachment comprising means connecting said rotatable vertical control ratchet to said ram stroke controlling oscillatory means, said connecting means including an oscillatory pawl carrying arm, a rod pivotally connected to said arm and a friction housing secured to said ram stroke controlling oscillatory means of said saddle, said friction housing embracing said rod to transmit the oscillatory motion of said saddle carried ram stroke controlling oscillatory means to said pawl carrying oscillatable arm, means on said friction housing for adjusting said housing to

oscillate said rod as said saddle carried ram controlling oscillatory means oscillates and to slide vertically as the saddle moves vertically.

4. In combination with a vertically movable and horizontally reciprocable shaper arm, a vertically movable ram carrying saddle, operating means for vertically moving the saddle, including a rotatable control ratchet, ram stroke controlling oscillatory means carried by said saddle for reciprocating said ram, and a ram attachment 10 comprising means connecting said rotatable vertical control ratchet to said ram stroke controlling oscillatory means, said connecting means including an oscillatory pawl carrying arm, a rod pivotally connected to said arm and a friction 15

housing secured to said ram stroke controlling oscillatory means of said saddle, said friction housing embracing said rod to transmit the oscillatory motion of said saddle carried ram stroke controlling oscillatory means to said pawl carrying oscillatable arm, means on said friction housing for adjusting said housing to oscillate said rod as said saddle carried ram controlling oscillatory means oscillates and to slide vertically as the saddle moves vertically, and adjustable stop means limiting the oscillation of said pawl carrying arm.
